ABSTRACT: In a keyboard instrument transposing adapters are provided to releasably connect between the key levers and the sound-actuating mechanisms so that a musical selection played in a key according to the key levers on the keyboard is transposed to produce sounds of a different key. Each adapter has members arranged for extensible and retractable sliding movement therebetween to adjust to a variety of distances between different key levers and sound-actuating mechanisms with a locking lever being operatively associated with the slidable members to hold them against further relative movement once the desired length is established. A plurality of the transposing adapters are arranged generally parallel to one another in the instrument and they extend upwardly on a diagonal to either side from the attachment at the key lever to the actuating mechanism.

SHEET 2 OF 2

FIG. 4

FIG. 5

ADJUSTABLE KEYBOARD-TRANSPOSING ADAPTER AND INSTRUMENT

This invention relates to a new and useful improvement in transposing keyboard instruments and more particularly to a novel transposing adapter for keyboard instruments and a transposing keyboard instrument utilizing a plurality of the adapters.

The purpose of transposing the keyboard of instruments such as pianos, organs and accordions and the like is that it permits persons having the ability to play in a familiar key such as the key of C to produce music in other keys using the fingering on the keyboard for the familiar key. Some attempts have been made to provide shifting structures to shift the keyboard from side to side for transposing the music. Such transposing devices, however, require substantial modification of the conventional instruments and would necessitate a new design with more space at each end thereof.

Accordingly, it is an object of this invention to provide an improved adapter for transposing a keyboard instrument to a higher or lower key than that in which the music is written while fingering the key levers in a familiar key.

Another object of this invention is to provide a novel extensible and retractable adapter for use in keyboard instruments which is applicable to a wide variety of keyboard instruments.

Yet a further object of this invention is provide a novel transposing adapter which can be readily applied to conventional pianos without changing the piano design.

In accordance with the present invention, in a preferred embodiment there is provided a readily extensible and retractable adapter which releasably interconnects between a selected key lever and a selected actuating mechanism for each sound-generating string in a piano. The adapter comprises a wire rod and a tubular body slidably telescoping over the rod. A lock latch on the tubular body moves between a locked position in which the wire rod is prevented from moving in the tubular body and a released position where the rod has free sliding movement within the tubular body. For the piano illustrated the upper end of the tubular body has an aperture through which the bridle wire secured on the piano action elbow extends and the lower end of the wire rod is bent to a particular shape and inserts into an aperture in the capstan on the rear of the key lever. A flexible band is provided to firmly but releasably secure the lower end of the wire rod to the capstan and a fastening collar firmly secures the tubular body to the bridle wire so that the motion imparted to the key lever is transmitted to the action elbow and in turn to the sound-generating strings. In a transposing instrument a plurality of adapters are arranged substantially in parallel to one another and diagonally upwardly to either side of the key lever to produce sound in a selected transposed instrument key.

Other objects, advantages and capabilities of the resent invention will become more apparent as the description proceeds taken in conjunction with the accompanying drawings, in which:

FIG. 1 is a diagrammatic front elevation view of a portion of a piano which has been transposed to play in the key of F using the fingering at the keyboard for the key of C;

FIG. 2 is a diagrammatic front elevation view showing a portion of the piano in FIG. 1 which has been transposed to play in the key of G using the fingering at the keyboard for the key of C;

FIG. 3 is a diagrammatic front elevation view of one piano action elbow and the range of positions of each adapter;

FIG. 4 is a front elevation view of an adapter connected in the piano represented in FIGS. 1-3; and

FIG. 5 is a side elevation view of the adapter connected in the piano in FIG. 4.

Referring now to the drawings, and in particular to FIG. 1, there is shown the general organization and arrangement of a transposing piano embodying features of the present invention. The piano parts shown and described are those of a standard 1911 Bachmann upright piano Ser. No. 46419. This instrument has a keyboard 11 with 88 key levers each represented by numeral 12 arranged side by side at one eleva-

tion and 88 piano action elbows each represented by numeral 13 arranged side by side at a higher elevation than the key levers with the piano action elbows being supported on the lower support portion of a bridle bar 14. A plurality of adapters 15 releasably cross-connect between a particular key lever 12 and a particular piano action elbow 13 as described more fully hereinafter. The sound-reproducing members of the piano are the strings located above the piano action elbows with only one being represented at 16. While a piano has been illustrated, it is understood that the present invention is applicable to other types of keyboard instruments, such as, organs, accordions and the like. Each string or group of strings of the piano has an actuating mechanism or action mechanism including the action elbow 13, striker rod 17, striker 18, hammer rod 19, and hammer 20 for causing the string or a group of strings to generate a sound when the hammer 20 is moved rearwardly. While only one string and an associated actuating mechanism has been shown and represented in FIG. 1, it is understood that the piano has at least one string and complete actuating mechanism for each piano action elbow 13 and key lever 12.

In the conventional piano, there is a key lever, actuating mechanism and a string or group of strings which are normally operatively interconnected for playing in a particular key and these members are hereinafter referred to as corresponding members. The corresponding key levers and action elbows are normally in a substantially vertical alignment so that the motion imparted to the key lever by the fingers is normally directed substantially vertically upward from the key lever to the action elbow. The corresponding key levers and piano action elbows for the normal or conventional piano are designated on the drawings with key designations which, proceeding from left to right for both the key levers and the piano action elbows, are A, B, B, C, C, D, E, E, F, F, G and A, and the sequence repeats from left to right with the last of the action elbows and key levers at the right side of the piano having a C designation. Some deviation from the actual vertical alignment for corresponding members results from having left- and right-side support posts 21 and 22 for structural strength purposes which are shown as separating intermediate of the piano action elbows 13. The instrument shown is arranged with a group of 28 piano action elbows to the left of left post 21 designated group I. There is a second group of 28 piano action elbows designated group II between the left and right sides of the posts 21 and 22, and a third group of 32 piano action elbows designated as group III to the right of the right post 22.

The transposing adapters 15 are connected in FIG. 1 so that sounds in the key of F are produced using the key of C fingering on the key levers 12 and for this setting each adapter 15 extends diagonally upwardly from one key lever toward the left side of the instrument to connect with a piano action elbow which is substantially offset to the left of the associated key lever to which it is connected. The key lever designated C for the key of C is shown as connected to the piano action elbow designated F and the next adjacent adapter connects the adjacent key lever designated B to the piano action elbow designated E and these connections proceeding from left to right then repeat so that in the complete instrument the adapters 15 are substantially parallel in engagement and along diagonal lines. It is to be noted that with this diagonal arrangement of the adapters 15 the first seven key levers on the left side of the keyboard are not in use and the last seven piano elbows on the right side of the piano are not in use.

For transposing from the key of C to the key of G the arrangement for the adapters is shown for the group III portion of the piano in FIG. 2 as representative. Here, each adapter 15 extends diagonally upwardly and toward the right side from the key lever to an associated piano action elbow. The full range of possible interconnections between a piano action elbow and a key lever for each adapter 15 is represented diagrammatically in FIG. 3. Adapter 15 is shown in the conventional position connecting the key lever designated C to a cor-

responding piano action elbow designated C and in this setting adapter has a vertical attitude. The variation from this setting for each adapter 15 is a range to the left, to one of seven key levers which is up in key and to the right to one of seven key levers which is down in key so that, including the conventional connection of key lever designated C to piano action elbow designated C, there is a possibility of 15 settings or connections for the adapter 15 for each setting the length of the adapter is different. In FIG. 3 the key levers are given a mechanical key designation corresponding to that of FIG. 1 and a musical key designation below the key lever showing whether the transposition is up or down.

With reference now to FIGS. 4 and 5, each white key lever has a lead weight 25 to equalize its center of gravity with that of the shorter black key levers which facilitates an even touch during the playing of the piano. A capstan 26 with an aperture 26a is mounted along the top at the rear of key lever. The forward portion of a piano action elbow 13 rests on a lower section of a bridle bar 14 above the capstan 26. The striker rod 17 is embedded in and extends upwardly from the top of the action elbow 13 as a part of the interconnecting linkage to the striker rod 17. A bridle wire 28 is also embedded in and extends upwardly from the top of the piano action elbow 13. Normally, the piano is equipped with a straight wooden actuating rod of a given length, not shown, to transmit motion between the key lever 12 and the piano action elbow 13. This actuating rod normally seats on top of the capstan 26 and is pivotally connected along the underside of the piano action elbow with a hinge pin. Another connecting rod, not shown, extends rearwardly of the actuating rod and is pivotally connected at both ends to the lower end of the actuating rod and to a lower action rail, not shown. In modifying the conventional piano, the above-described upper hinge pin is removed the actuating rod is then moved to an out-of-the-way position at the rear or fully removed from the piano. Also in the modification of a conventional piano the bridle strap wire 28 normally extends upwardly and outwardly and has a curved end portion but this is modified so that it is straight and extends directly forwardly of the top of the piano action elbow as shown.

Each transposing adapter 15 shown in detail in FIGS. 4 and 5 comprises a lower solid wire rod 31 which slidably interfits or telescopes in an upper tubular body 32 to facilitate the changing of the effective length between the opposite ends of the rods 31 and the tubular body 32, by sliding the rod in and out of the tubular body. In order to lock the tubular body and rod against sliding movement once the desired length is achieved, there is provided a locking lever 33 which pivotally mounts on the side of the tubular body. For pivotally supporting the locking lever 33, there is provided a yokelike collar member having a pair of spaced side arms 35 and 36 to slidably receive the locking lever 33 and a pivot pin 37 extends through apertures in the arms and the locking lever. This supports the locking lever 33 so that it will pivot from an upstanding out-of-the-engagement position where it has a vertical attitude to the forwardly projecting locking position shown in full lines. The inner edge 33a of the locking lever is curved or rounded and extends through an elongated vertical slot 38 along the side of the tubular body through which the curved edge 33a will extend when pivoted downwardly to the locked position so as to bear directly against the wire rod 31 and force it into a frictional engagement between the inner surface of the tubular body and the curved surface 33a of the lever 33 and in this way the tubular body and wire rod are locked together to prevent further relative movement therebetween.

The wire rod 31 is provided with a releasable connector portion at its lower end portion and to this end it is bent along its length into a particular configuration which includes an upper straight section 31a on which the tubular body slides, and a lower hooklike portion having a gradually inclined section 31b which extends rearwardly, a rearwardly inclined extending section 31c which extends along the horizontal, and a gradually inclined upturned end section 31d. The wire rod

shown is 1/16-inch piano-type wire having a uniform cross section and is of a size so that the lower end sections 31c and 31d will slidably insert into the capstan aperture 26a. The tubular body may be made of brass or like relatively heavy material which assists in the piano playing action. A collar 41 on the inclined rod section 31b has a setscrew 42 threaded in the collar to lock it at a selected position. A flexible band 43 of rubber or the like extends around the wire rod section 31b and is held by the locking collar 41, the band 43 then extends over the capstan, and around the upturned end section 31d to releasably secure the lower end of the wire rod to the capstan 26. A section of rubber tubing 44 is disposed on the wire rod between the collar 41 and the capstan 26 to provide a damping effect during the playing of the instrument. The flexible band 43 serves to hold the lower end of the rod in place and to hold the key levers level in their normal position.

At the upper end of the adapter 15 there is provided a releasable connector portion in the form of an aperture 45 in tubular body 32 which is sized to slide over projecting out-turned end of the bridle wire 28. Clearance is provided between the wall of aperture 45 and the bridle wire. Again, a length of flexible tubing 46 of rubber or the like is provided between the elbow 13 and the tubular body 32 and another length of flexible tubing 47 on the outer end of the tubular body 32 to provide for the damping of noise. A locking collar 48 having a setscrew 49 is disposed on the other end of the bridle wire 28 and engages tubing 47 to hold the tubular body on the bridle wire. This attachment at the upper end of the tubular body permits the adapter to pivot about bridle wire 28 and swing from side to side through a substantial angle as represented in dashed lines in FIG. 4 and also shown in FIG. 3 to connect to the selected key lever 12.

For changing the setting of the instrument from one key to another key the inner end of band 43 is slipped over the outer end section 31d of the wire rod and the wire rod is then moved forwardly and out of the capstan aperture 26a. The lock lever 33 is pivoted up to its release position so that its curved edge 33a no longer bears against the wire rod 31 and the wire rod is then free to slide in the tubular body to permit lengthening or shortening of the distance between the opposite ends thereof so as to extend a selected key lever 12 and a selected piano action elbow according to the key desired. The lower end section of the wire rod is then inserted into the selected capstan aperture and, once the rod 31 is in place on the capstan, the flexible band 43 is slipped over the free end section 31d and the lock lever 33 is pivoted down to the lock position shown so that it again bears against the inner wall of the tube to lock it against relative sliding movement therebetween. This is repeated for each next adjacent key lever and piano action elbow and so on across the piano. In the playing of the instrument the motion imparted by the fingers to each key lever 12 is transmitted through the adapter 15 to the piano action elbow 13 which in turn will cause the movement of the striker hammer against the string or strings to produce musical sounds.

From the foregoing, it is apparent that the transposing adapter and instrument will materially assist composers, pianists and the like in transposing to a desired and appropriate key. Songs written for other instruments and in difficult keys can be played with greater ease.

Although the present invention has been described with a certain degree of particularity, it is understood that the present disclosure has been made by way of example and that changes in details of structure may be made without departing from the spirit thereof.

What is claimed is:

1. A transposing adapter for a keyboard instrument arranged to transmit motion between selected key levers and sound-actuating elbows of the instrument, said adapter comprising first and second telescoping members, said members being longitudinally slidably one relative to the other to adjust to a selected length between the opposite end portions thereof and having the opposite end portions adapted to releasably

connect between a selected key lever and a selected sound-actuating elbow, and releasable lock means to hold said first and second members against relative movement therebetween when said end portions are connected between a selected key lever and sound-actuating elbow.

2. A transposing adapter as set forth in claim 1 wherein said first member is in the form of a tubular body and said second member is in the form of a wire rod which telescopes in said tubular body.

3. A transposing adapter as set forth in claim 2 wherein said tubular body has an aperture adjacent its outer end for slidably receiving a complementary outwardly projecting section on the sound-actuating elbow on the instrument about which the tubular body may pivot.

4. A transposing adapter as set forth in claim 2 wherein said wire rod is sized to extend through a receiving aperture operatively associated with the key lever.

5. A transposing adapter as set forth in claim 4 wherein said wire rod is bent to provide a generally hooklike lower end portion with a gradual upturned outer end.

6. A transposing adapter as set forth in claim 2, said releasable lock means includes a pivotal lever arranged to pivot between an upright release position permitting slidable movement between said member and a forwardly extending lock position preventing further sliding movement.

7. A transposing adapter as set forth in claim 6 wherein said lever has a rounded inner edge adjacent the pivot which extends through a vertical slot in the tubular body to force the wire rod against an inner sidewall of the tubular body to lock said tubular body and wire rod together.

8. A transposing adapter as set forth in claim 2 wherein said tubular body is made of a relatively heavy metal material.

9. A transposing adapter as set forth in claim 2 wherein said wire rod is a piano-type wire.

10. In a keyboard instrument having a keyboard with a plurality of key levers, a plurality of actuating elbows adapted to cause the actuation of a plurality of sound-generating strings for producing sounds in different keys, and a plurality of transposing adapters for transmitting motion between selected key levers and selected actuating elbows so that a musical selection played in a selected key according to the fingering on the keyboard is transposed to another key at the sound-generating strings, each said adapter including first and second longitudinally adjustable telescoping members, said telescoping members being longitudinally slidable one relative to the other to adjust to a selected length between the opposite end portions thereof and having the opposite end connector portions releasably connected between a selected key lever and a selected actuating elbow and a releasable lock to hold said first and second members against relative movement therebetween once said members are positioned between a

selected key lever and a selected actuating elbow.

11. In a keyboard instrument as set forth in claim 10 wherein each adapter extends from the selected key lever upwardly along a diagonal line to the selected actuating elbow and the adapters are arranged substantially parallel to one another between adjacent key levers and actuating elbow.

12. In a keyboard instrument as set forth in claim 11 wherein each adapter pivots at its point of attachment to the actuating elbow to swing from side to side to connect the end connector portion with a selected key lever on either side of a key lever vertically in line with the attached actuating elbow.

13. In a keyboard instrument as set forth in claim 12 wherein said adapter extends to one of seven key levers on either side of the key lever vertically in line with the attached actuating elbow.

14. In a piano having a keyboard including a plurality of finger-actuated key levers with a capstan at the rear of each lever, a plurality of actuating mechanisms with each mechanism including an action elbow with a bridle wire, sound-generating strings actuated by the actuating mechanism to produce sounds in different keys, the actuating mechanism and key lever for playing in a particular key being in a substantially vertical alignment, a plurality of transposing adapters for transmitting motion between selected key levers and selected actuating mechanisms so that a musical selection played in a selected key according to the fingering on the keyboard is transposed to another key at the strings, each said adapter including an upper tubular body and a lower wire rod slidably telescoping in the tubular body, said tubular body having an aperture receiving the bridle wire on the associated action elbow and said wire rod having an end portion inserted into an aperture on an associated capstan of a selected key lever, a releasable lock pivotally mounted on the tubular body to lock against further sliding movement after said tubular body and wire rod are in place between a selected key lever and a selected actuating mechanism.

15. In a piano as set forth in claim 14 wherein said wire rod has a generally hooklike lower end portion disposed in the capstan with an upturned lower end projecting rearwardly from the capstan and a flexible band extending around the hooklike lower end portion to secure the wire rod to the capstan.

16. In a piano as set forth in claim 15 including a locking collar on the hooklike portion to hold the band and a length of flexible tubing on the wire rod between the collar and capstan and to dampen vibrations.

17. In a piano as set forth in claim 15 including a locking collar on the end of the bridle wire to releasably secure the tubular body to the action elbow and a flexible tubing between the locking collar and tubular body and between the tubular body and action elbow to dampen sound vibrations.
